[57] CLAIM

The ornamental design for a vehicle auxiliary compartment, as shown and described.

DESCRIPTION

FIG. 1 is a perspective view of a vehicle auxiliary compartment showing my new design, it being understood that the broken lines are for illustrative purposes only; FIG. 2 is a top plan view thereof; FIG. 3 is a bottom plan view thereof; FIG. 4 is a side elevational view thereof; FIG. 5 is a side elevational view thereof opposite to that shown in FIG. 4; FIG. 6 is a front elevational view thereof; and FIG. 7 is a rear elevational view thereof.

FIG. 4.

FIG. 5.

FIG. 6.

FIG. 7.
